United States Patent Office

Des. 181,933
Patented Jan. 21, 1958

181,933

CHAIR

John J. Lubberts and Lambert J. Mulder, Grand Rapids, Mich., assignors to Tomlinson of High Point, High Point, N. C., a corporation of North Carolina

Application April 16, 1957, Serial No. 45,756

Term of patent 14 years

(Cl. D15—1)

We claim:

The ornamental design for a chair, substantially as shown.
